SPRING CUSHION CONSTRUCTION

John Lupaloff, Detroit, Mich., assignor to L. A. Young Spring & Wire Corporation, Detroit, Mich.

Application November 9, 1946, Serial No. 708,827

10 Claims. (Cl. 5—274)

1

This invention relates to improvements in spring cushion construction.

The principal objects of this invention are:

First, to provide a spring cushion structure in which the springs are supported to permit substantial individual yielding action to load and at the same time, transmit a substantial portion of the load to adjacent springs and to provide an effective upholstering supporting surface.

Second, to provide a structure having these advantages which is economical to produce, durable in use and substantially noiseless.

Third, to provide a structure having these advantages in which the springs are substantially spaced preventing their clashing and also economizing on the number of springs required.

Further objects and advantages pertaining to the details and economies of the invention will be apparent from the description to follow. The invention is further pointed out in the claims.

A structure which embodies the features of the invention is illustrated in the accompanying drawing, in which:

Fig. 1 is a fragmentary front perspective view of an automobile seat cushion embodying my invention.

Fig. 2 is a fragmentary plan view thereof with the upholstery removed, portions being conveniently illustrated.

Fig. 3 is an enlarged fragmentary plan view showing certain of the structural features or details of my invention.

In the accompanying drawing I have illustrated an embodiment of my invention in a rear seat automobile cushion. While my invention is well adapted for embodiment in cushions of substantial size, it will be understood that the size and shape may be greatly varied.

In the embodiment illustrated the body springs 1 are of the hourglass helical coiled type. The bottom border frame 2 and the cross supports 3 are of suitable structure or design to support the body springs. However, this bottom structure as far as details are concerned form no part of my present invention. The top border frame designated generally by the numeral 4 comprises a so-called extension front frame member 5, rear frame members 6 and end extension frame members 7. These are of known design.

The springs 1 are arranged in longitudinal and transverse rows and may be substantially spaced as illustrated. The front border springs are secured to the front border frame member 5 by means of clips 8. The end border springs are secured to the end border frame member by

2

similar clips 8. The rear border springs are secured to the rear border frame member by wire clips 9. The springs of the intermediate longitudinal rows have their top coils connected by 5 the helical tie members 10. The transverse row of springs 11 adjacent the border springs at one end of the cushion are connected to the border springs by means of the crossed helical tie members 12. The springs are further connected by 10 means of the webs of fabric 13 which are of substantial width and are slidably rove zig-zag through the top coils of adjacent springs of adjacent longitudinal rows. The ends of these webs are secured by means of clips 14 to top coils of 15 the end row of border springs at one end of the structure and are connected at 15 to the springs of the row 11 which are as stated connected by the crossed helicals to the end border springs at the other end of the cushion. This provides a 20 very effective support for the springs and one which permits substantial individual springing or yielding and at the same time the load is well distributed throughout the springs adjacent the points or area of compression. The webs and 25 the helical tie members provide an effective upholstery supporting surface.

Structures embodying my invention may be very economically produced, both in the number of springs used and in the assembly thereof. The 30 springs are effectively supported in spaced relation so there is no possibility of their clashing with adjacent springs and they are effectively supported in upright position.

I have not attempted to illustrate or describe 35 various embodiments or adaptations to different types of seat cushions and back cushions as it is believed that this disclosure will enable those skilled in the art to embody or adapt my invention as may be desired.

Having thus described my invention, what I 40 claim as new and desire to secure by Letters Patent is:

1. In a spring structure the combination of a 45 top border frame, coiled body springs arranged in longitudinal and transverse rows, the top coils of the border springs being secured to the border frame, helical spring tie members connecting the top coils of adjacent springs of the longitudinal rows, the top coils of one end row of border 50 springs being connected to the top coils of the adjacent transverse row of springs by crossed helical tie members, and webs of fabric of substantial width slidably rove zig-zag through the top coils of adjacent springs of adjacent longitudinal rows and secured at one end to the 55

springs connected to the springs having the crossed helical tie connection to the adjacent end border springs and at their other ends to end border springs at the opposite end of the structure.

2. In a spring structure the combination of a top border frame, coiled body springs arranged in longitudinal and transverse rows, the top coils of the border springs being secured to the border frame, helical spring tie members connecting the top coils of adjacent springs of the longitudinal rows, and webs of fabric of substantial width slidably rove zig-zag through the top coils of adjacent springs of adjacent longitudinal rows and secured at one end to springs having spring tie connection to the adjacent end border springs and at their other ends to end border springs at the opposite end of the structure.

3. In a spring structure the combination of a top border frame, coiled body springs arranged in longitudinal and transverse aligned rows, the top coils of the border springs being secured to the top frame, and webs of fabric of substantial width slidably rove zig-zag through the top coils of adjacent springs of adjacent rows and secured at one end to border springs secured to the top frame and at their other ends to springs having resilient connections to the top border frame.

4. In a spring structure the combination of a top border frame, coiled body springs arranged in rows in at least one direction, resilient connections for the top coils of the springs of the rows, the border body springs being secured to the frame, and webs of fabric of substantial width rove zig-zag through top coils of the springs of adjacent rows and secured at one end to springs secured to the top frame and at their other ends to springs resiliently connected to the top frame.

5. In a spring structure the combination of a top border frame, coiled body springs arranged in rows, the top coils of the end springs of the rows being secured to the top frame, and webs of fabric slidably rove zig-zag through the top coils of adjacent springs of adjacent rows and secured at one end to end springs of the rows connected to the top frame and at their other ends to springs adjacent to and having resilient connections to end springs at the other ends of the rows connected to the top border frame.

6. In a spring structure the combination of a top border frame comprising front, rear and end members, coiled body springs arranged in

longitudinal rows, the top coils of front, rear and end border springs being secured to the front, rear and end members of the border frame respectively, resilient tie members connecting the

5 top coils of adjacent springs in the rows, and webs of fabric rove zig-zag through the top coils of adjacent springs of adjacent rows and secured at one end to springs connected to one end member of the border frame and at the other end to 10 springs having resilient tie connections to the border springs connected to the other end of the frame.

7. In a spring structure the combination of a top border frame comprising front, rear and 15 end members, coiled body springs arranged in longitudinal rows, the top coils of the front, rear and end border springs being secured to the front, rear and end members of the border frame respectively, tie members connecting the top coils of adjacent springs in the rows, and webs of fabric rove zig-zag through the top coils of adjacent springs of adjacent rows.

8. In a spring structure the combination of a border frame, coiled springs, the top coils of the border springs being secured to the border frame, and webs of fabric of substantial width slidably rove zig-zag through the top coils of adjacent springs and connected at one end to springs connected to the border frame and having a resilient connection at their other ends to the border frame.

9. In a spring structure the combination of opposed frame members, coiled springs arranged in rows between said frame members, the top coils of the end springs of the rows being secured to the opposed frame members, and webs of fabric slidably rove zig-zag through the top coils of adjacent springs of adjacent rows to yieldably support the springs and to provide an upholstery supporting surface, and resilient connections for 30 adjacent springs of the rows.

10. In a spring structure the combination of opposed frame members, coiled springs arranged in rows between said frame members, the top 45 coils of the end springs of the rows being secured to the opposed frame members, and webs of fabric slidably rove zig-zag through the top coils of adjacent springs of adjacent rows to yieldably support the springs and to provide an upholstery supporting surface.

JOHN LUPANOFF.
